GEAR HOUSING FOR JALOUSIE TYPE WINDOWS

Donn C. Blanchard, Miami, Fla., assignor to Stanley Building Specialties Company, North Miami, Fla., a corporation of Florida

Application November 12, 1954, Serial No. 33,074

Term of patent 14 years

(Cl. D10—10)

Fig. 1.

Fig. 2.

Fig. 3.

Fig. 4.

Figure 1 is a perspective view of a gear housing for Jalousie type windows showing my new design, Figure 2 is a side elevation thereof, Figure 3 is a front elevation thereof, and Figure 4 is a top plan view thereof. The sides of the gear housing not shown are substantially plain in appearance.

I claim:
The ornamental design for a gear housing for jalousie type windows, as shown and described.
